UNITED STATES PATENT OFFICE.

COLIN J. CAMPBELL, OF NEWARK, NEW JERSEY, ASSIGNOR TO THE STANDARD SIGNAL CORPORATION, A CORPORATION OF NEW YORK.

SIGNALING APPARATUS.

Application filed March 18, 1920. Serial No. 366,931.

To all whom it may concern:

Be it known that I, COLIN J. CAMPBELL, a citizen of the United States, and a resident of Newark, in the county of Essex and State 5 of New Jersey, have invented certain new and useful Improvements in a Signaling Apparatus, of which the following is a full, clear, and exact specification.

This invention relates more particularly 10 to a class of apparatus adapted to be used in conjunction with vehicles.

My invention has for its object primarily 15 to provide an apparatus designed to be employed on an automobile, autotruck or other vehicle for indicating the direction to the right and left in which the vehicle is about to turn and to also indicate when the vehicle is about to be brought to a standstill, and which is of a form serving to enable the 20 signals to be observed either during the day or at night, in order to avoid the occurrence of accidents by giving timely warnings especially to the occupants of approaching vehicles which may be travelling toward the 25 vehicle from the rear. The invention resides mainly in the provision of an upper and lower chamber adapted to be applied to a vehicle, the lower chamber having spaced illuminated signals of different colors in the 30 forms of exposure windows with indicia to indicate opposite directions in which the vehicle is about to turn, and the upper chamber having a single illuminated signal of still another color also in the form of an exposure 35 window with indicia to indicate when the vehicle is at a standstill. Exterioly of the lower chamber is an oscillatory pointer adapted to be swung to and from each of the illuminated signals of the lower chamber 40 so that the attention of observers may be directed during day light to the respective signals. Pivoted exteriorly of the upper chamber is a semaphore which normally curtains the illuminative signal of this 45 chamber for being swung from and in front of the signal so that it may be exposed to view also during daylight. In the lower chamber may be two lamps, while in the upper chambers may be one lamp, these 50 lamps serving when lighted to illuminate

the signals during darkness, and all of the lamps are preferably lighted through the medium of an electric circuit.

Other objects of the invention are to provide in the lower chamber an armature 55 which is connected to the pointer and interposed in the circuit so that it will be swung to either of the illuminated signals of the lower chamber when the circuit is closed; to provide in the upper chamber a second 60 armature which is connected to the semaphore and interposed in the circuit so that when the circuit is closed the semaphore will be moved from in front of the illuminated signal of the upper chamber; and to provide 65 in the semaphore a window whereby part of the illuminated signal of the upper chamber will be exposed to view when the semaphore curtains the signal for serving as a tail light for the vehicle. 70

A further object of the invention is to provide a signaling apparatus of a simple, efficient and durable construction which may be made in any suitable size and shape.

With these and other objects in view the 75 invention will be hereinafter more fully described with reference to the accompanying drawings forming a part of this specification in which similar characters of reference indicate corresponding parts in all the 80 views, and will then be pointed out in the claims at the end of the description.

In the drawings, Figure 1 is a front elevation, partly broken away, of my improved 85 signaling apparatus.

Fig. 2 is a longitudinal vertical section, partly broken away, taken through the interior of the casing.

Fig. 3 is a detail view showing a detail 90 sectional view taken on the line 3—3 of Fig. 1 as well as showing the switch for electrically operating the signals of the apparatus as applied to the post of the steering wheel of a vehicle, and

Fig. 4 is a diagrammatic view of the electric circuits used in the apparatus. 95

The apparatus has a lower chamber 10, an upper chamber 11, and these chambers are provided interiorly of a casing, as 12, adapted to be applied preferably on the rear end 100

2
of an automobile, autotuck or other vehicle, as 13, having a post 14 with a steering wheel 15 for piloting the vehicle. The casing 12 may be of any suitable shape and size 5 as well as being made of sheet metal or other material, though the form of casing illustrated is substantially rectangular to provide a front wall 16, rear wall 17, bottom wall 18, top wall 19 and side walls 20, 21. The upper 10 and lower chambers 10 and 11 are provided by dividing the interior of the casing with a transverse partition 22 which extends from near the central part of the rear wall 17 to the front wall 16 of the casing. 15 In the part of the front wall 16 under the partition 22 of the casing are two spaced illuminated signals, as 23 and 24, both composed of exposure windows of glass or other transparent or translucent material which 20 are fitted in spaced openings 25 and 26 leading into the lower chamber 10 of the casing, and these windows are preferably of different colors, such as the window 23 being blue, while the window 24 is yellow, in order that the signals may be easily observed 25 as well as being readily distinguished from each other during daylight. Inscribed or otherwise provided on the windows 23 and 24 may be indicia 27 and 28 respectively, 30 the indicia 27 consisting of the word "Left" and the indicia 28 consisting of the word "Right" so as to indicate to an observer the direction in which the vehicle is about to turn. In the part of the front wall 16 above 35 the partition 22 of the casing is a single or third illuminated signal 29 preferably in the form of an exposure window of glass or other transparent or translucent material which is mounted in an opening 30 leading into the upper chamber 11 of the casing. The signal or window 29 is preferably red so that it is distinguishable from the windows or signals 23 and 24, and on this window is inscribed or otherwise provided indicia, as 31, consisting of the word "Stop" 40 for indicating to an observer when the vehicle is about to be brought to a standstill. When the signals or windows 23, 24, 29 are made of transparent material their coloring 45 may be so provided that the indicia 27, 28, 31 will be free of color or clearly transparent, in which instance the indicia will be plainly and unmistakably observable during darkness when illuminated by lighting the interior of the chambers of the casing, as 50 will be hereinafter more fully explained. 55 Extending interiorly of the lower chamber 10 from the rear wall 17 of the casing in spaced proximity to the partition 22 is a somewhat elongated substantially U-shaped bracket 32 arranged so that its bridging member 33 is disposed crosswise of the rear wall, while the leg members 34 and 35 are disposed in downwardly diverging directions. Depending from the central part of

the underside of the bridging member 33 and between the leg members 34 and 35 of the bracket 32 is a lug 36 which is spaced from the rear wall 17 of the casing 75 and between the leg members 34 and 35 of the bracket 32 is a lug 36 which is spaced from the rear wall 17 of the casing and at some distance above the partition 22 is a bracket 37 which may be approximately the shape of an inverted L to provide a member 38 disposed transversely of the rear wall as 75 well as providing an inclined depending arm 39. Hanging downwardly from the underside of the transverse member 38 of the bracket 37 in spaced relation to the depending arm 39 is a lug 40 which is spaced from the rear wall of the casing. Extending interiorly of the lower chamber 10 of the casing from the front wall 16 and between the spaced signals 23 and 24 may be a vertically disposed partition 41 for screening the second one of these signals when the other signal is illuminated, and in the top wall 19 of the casing may be provided a window 42 to allow the light from the upper chamber to illuminate a license sign 90 when provided on a vehicle above the casing. 95

On the exterior of the front wall 16 of the casing 12 between the illuminated signals 23 and 24 is an oscillatory pointer, as 43, which is preferably in the form of an arrow shaped bar normally arranged in an upright position. Protruding rightangularly from the bar in spaced proximity to its lower end is a pin or stud 44 which is journaled in a bearing provided in the front wall of the casing, and this stud is of a length so that it protrudes interiorly of the lower chamber 10 of the casing. On the end of the stud within the lower chamber is a downwardly disposed link, as 46, having preferably an elongated opening or slot 47 therethrough, while the lower end of the pointer 43 may be weighted, as at 48, in order to maintain the pointer normally movable in an upright position between the signals 23 and 24 so that its upper end may be swung toward and from each of these signals. 110

Exteriorly of the front wall 16 of the casing and normally curtaining the illuminated signal 29 is a semaphore 49 adapted to be swung upwardly and downwardly from and in front of the signal. This semaphore is preferably in the form of an elongated plate or panel 50 which is normally arranged crosswise of the wall 16 of the casing in a fashion so that one of its ends is in front of the signal or window 29, and projecting from part of one face of the panel in spaced proximity to its other end is a pin or stud 51 which is journaled in a bearing in the front wall so that the free end of the stud extends into the upper chamber 11 of the casing. On one end of the stud 51 interiorly of the upper chamber is a depending 125 130

link 52 having a circular opening 53 therethrough, and the end of the panel 50 contiguous to the stud 51 is weighted, at 54, for serving to cause the other end of the panel to swing downwardly when swung upwardly above the signal 29. On the front wall of the casing over the signal 23 is a protruding flange, or lug or bracket, as 55, which serves as a stop for limiting the downward movement of the second end part of the panel 50 so that the panel will be movably held normally in front of the signal 29, and through this second end part of the panel is an opening, as 56, for exposing a portion of the red signal 29 to serve as a tail light especially during darkness when the apparatus is in use on a vehicle.

On the partition 22 and in the lower chamber 10 of the casing 12 back of the signal or window 23 is a lamp 57, while on the partition in the lower chamber and back of the signal or window 24 is another lamp 58, and also on the partition in the upper chamber 11 of the casing is a third lamp 60 which is disposed back of the signal or window 29. These lamps are of well known types adapted to be electrically lighted by being interposed in a normally open electric circuit, as 61. This circuit may derive its supply of current from any suitable source, such as from a battery, as 62, suitably arranged in the vehicle upon which the apparatus is employed. Interposed in the circuit 61 and held on the leg members 34 and 35 of the bracket 32 of the lower chamber 10 of the casing 12 are two magnets, as 63 and 64, which are arranged so that their cores are in spaced opposition. To the lug 36 and to the rear wall 17 of the casing is pivoted, at 65, the upper end of an oscillatory armature or electro-conductive bar 66. This armature is thereby suspended between the magnets 63 and 64 for being attracted separately to the cores of the magnets when energized, and the armature is of a length so that its lower end extends in opposed relation to the lower end of the link 46 of the pointer 43. Protruding from the armature 66 as well as being movably disposed in the slot of the link is a pin 67 so that when each of the magnets is energized the armature will be swung to the energized magnet and in turn the pin 67 will cause the link 46 to be likewise swung for swinging the pointer 43 toward one of the signals or windows 23 and 24. Interposed also in the circuit 61 and held on the arm 39 of the bracket 37 in the upper chamber 11 of the casing 12 is a magnet 68 having its core disposed toward the lug 40 of the bracket, and between this lug and rear wall 17 of the casing is pivoted, at 69, the upper end of an armature or electro-magnetic bar 70 adapted to be attracted to the core of the magnet 68 when energized, and the armature 70 is of a length

so that its lower end is in opposition to the link 52 of the stud 51 of the semaphore or panel 50. Extending from the armature 70 is a pin 71 which is movably disposed in the opening of the link 52 so that when the magnet 68 is energized and the armature 70 is swung to the core of the magnet the semaphore or panel 50 will be swung upwardly from in front of the signal or window 29 of the casing 12. In order to allow the circuit 61 to be conveniently closed and opened by the chauffeur of a vehicle having the signal apparatus applied thereto, a switch, as 72, is interposed in the circuit as well as being employed on the post 14 of the steering wheel 15 of the vehicle. This switch may be of any suitable form, but I prefer to use the type of switch as disclosed in my pending application serially numbered 366,930, filed March 18, 1920, and which is provided with a contact, as 75, engageable by movable contacts, as 76, 77, 78, Figs. 3 and 4, adapted to be manually operated separately by the chauffeur of the vehicle for closing the circuit at intervals, as will be hereinafter more fully explained.

The electric circuit 61 may consist of any appropriate lay-out of wiring, as occasion requires, the lay-out diagrammatically illustrated consisting of a wire 79 leading from one terminal of the battery 62 to ground, as 80, which may be provided by the casing 12. From the second terminal of the ground 80 leads a wire 81 to the fixed contact 75 of the switch 72. Also from the battery is a wire 82 which leads to a binding post 83 provided on the partition 22 of the casing 12, and leading from this binding post is a wire 84 connected to a switch 85 adapted to be moved into and out of engagement with the contact 86 of a wire 87 which leads to one pole of the lamp 60 having its second pole grounded, as at 89. Connected to the switch 77 is a wire 90 leading to a binding post 91 provided on the partition 22 of the casing 12, and connected to the wire 90 is a wire 92 leading to one terminal of the magnet 68 of the upper chamber 11 of the casing, this magnet having its second pole grounded, as at 93. Connected to the switch 76 is a wire 94 which leads to a binding post 95 arranged on the partition 22 of the casing 12, and to the wire 95 is connected a wire 96 leading to one terminal of the magnet 64 and to one pole of the lamp 57 in the lower chamber of the casing. The second terminal of the magnet 64 is grounded, as at 98, and the second pole of the lamp 57 is grounded, as at 99. Leading from the switch 78 is a wire 100 which is connected to a binding post 101 also provided on the partition 22 of the casing 12, and from the binding post 101 is a wire 102 leading to one terminal of the magnet 63 which has its second terminal grounded, as at 103. Con-

ected to the wire 102 is a wire 104 which leads to one pole of the lamp 50 of the lower chamber of the casing, and the second pole of this lamp is grounded, as at 105.

5 To operate the apparatus for setting the various signals at required times the switch 85 is closed upon the contact 86, and during the travel of the vehicle when it is desired to signal to observers that the vehicle is about 10 to turn to the right, the switch 78 is moved into engagement with the contact 75. The circuit will be closed from the battery 62 over wire 79, through ground 80, through the engaged contacts 75 and 78, over wire 15 100, through the post 101, over wire 102 to and through the magnet 63 and to ground 103. From the battery the circuit will also be closed through ground 80, and through ground 103 to the magnet 63. From the wire 20 102 the circuit will be completed over wire 104, through lamp 58 and through grounds 105, 103 and 80. The lamp 58 will thereby be lighted to illuminate the signal 23 and indicia 27. The magnet 63 will also be energized for attracting to its core the armature 66 which in turn will cause the pointer 25 43 to be swung to the signal 23. When it is desired to signal to observers that the vehicle is about to turn to the left, the switch 30 76 is closed upon the contact 75, and the circuit will be closed from the battery 62 and over wire 79, through ground 80 to and through the contacts 75 and 76, over wire 94, through post 95, over wire 96 to and through 35 35 the magnet 64 and lamp 57, and through grounds 80, 98, and 99. The energizing of the magnet 64 will attract to its core the armature 66 for swinging the pointer 43 to the signal 24 and indicia 28, and the closing 40 40 of the circuit will light the lamp 57 to illuminate this signal. When it is desired to indicate to observers that the vehicle is about to be brought to a standstill, the switch 77 is closed upon the contact 75. The circuit 45 will then be closed from the battery 62, through ground 80, through contacts 75, 77, over wire 90, 92, to and through the magnet 68 and through grounds 80, 93. The armature 70 will by the energizing of the magnet 50 68 be attracted to its core for swinging the semaphore 49 upwardly from in front of the signal 29 and indicia 31 to indicate stopping of the vehicle. With the closing of the switch 85 upon the contact 86 the lamp 55 60 will be lighted by the circuit being closed from the battery 62, over wire 82, through post 83, over wire 84, through the contacts 85, 86, over wire 87 and through grounds 80 and 89 for illuminating the signal 29 and indicia 31 as well as for causing the signal 29 to serve as a tail light for the vehicle by the red color of this signal being displayed through the opening 56 of the semaphore 49. The lamp 60 also serves

when lighted to illuminate the license sign 65 of the vehicle when arranged over the casing by the rays of its light passing through the window 42. For use at night the switch 85 is closed and remains closed, the stop signal being given by the shutter 49.

70 In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof. Moreover, in this present application I do not claim the specific forms of the casing 12 with the pointer 43 and the semaphore 49 as these parts are made subject matters of my pending application for a patent, Sr. No. 366,929 filed March 18, 1920. 75 80 85

Having thus described my invention, I claim as new and desire to secure Letters Patent:—

90 1. In combination with a casing having an opening in one wall with an exposure window therein, said exposure window having a legend thereon, a pin journaled in and extending through said wall, a signal element fixed to said pin exteriorly of the casing and adapted to be swung toward and away from said legend, means to normally bring the signal element at rest in one position, and means operable at will to swing said signal element to another position; said last named means including a crank having one end fixed to said pin within said casing, a normally vertical armature bar pivoted in the casing at its upper end, means pivotally and slidably connecting said crank to the lower end of the armature bar, a magnet 95 fixed in the casing for attracting and swinging said armature bar, and a mounting bracket within the casing comprising an angle bar having a horizontal portion to which the armature bar is pivoted, and an inclined portion to which the magnet is fixed.

100 105 110 115 120 125 2. A casing and signal including a hollow body having a front wall, a removable rear wall for said body with a horizontal partition fixed to and protruding therefrom to a point adjacent the front wall and dividing the interior of the body into a lower chamber and an upper chamber, a second and vertical partition fixed to and extending from the front wall towards the rear wall for dividing the lower chamber into two sub-chambers, two signal windows, one in the front wall of each of the sub-chambers, said signal windows being readily distinguishable, a third signal window distinguishable from the others and disposed in the front wall of the upper chamber of the

body, illuminating means for the chamber carried by the horizontal partition, signal members cooperating with the windows and pivoted to the front wall of the body, and electromagnets fixed to the removable rear wall of the body and having operative connections with the signal members, said operative connections being separable for allowing removal of the rear wall of the body

and separation of the electromagnets from 10 the signal members.

This specification signed and witnessed this 16th day of March, A. D. 1920.
